UNITED STATES PATENT OFFICE.

ALBERT R. THOMPSON, OF SAN JOSE, CALIFORNIA, ASSIGNOR TO ANDERSON-BABENROVER MFG. CO., OF SAN JOSE, CALIFORNIA, A CORPORATION OF CALIFORNIA.

COOKER.

1,202,243.

Specification of Letters Patent. Patented Oct. 24, 1916.

Application filed February 9, 1916. Serial No. 77,128.

To all whom it may concern:

Be it known that I, ALBERT R. THOMPSON, a citizen of the United States, residing at San Jose, in the county of Santa Clara and 5 State of California, have invented certain new and useful Improvements in Cookers, of which the following is a specification.

My invention relates to that class of cookers, for use in the canneries, in which the 10 filled and closed cans are rolled along a path within a heated box. In cookers of this type, in addition to the recognized advantage of a continuous rolling of the cans, namely, a more equal application of the heat 15 and consequent shortening of the time of cook, there has always been the problem of obtaining a sufficiently extensive can-path necessary for cooking, which while giving capacity to the machine, will not unduly enlarge its proportions; because economy in 20 floor-space is a consideration of prime importance. It is evident, for this reason, that a cooker which is relatively short and narrow is much to be preferred in comparison 25 son with one which is relatively long and wide, even though both may have equal capacity and length of can path. Improvement has, consequently, heretofore, found expression in providing a can-path of a tortuous nature, examples of which are to-and-fro paths, zig-zag paths and spiral or helical paths, all of which give opportunity for a box which will occupy relatively small 30 floor space. It must be noted, however, that 35 increase of capacity by merely increasing, by duplication, the number of paths, thereby adapting the cooker for plural can-lines, is not improvement of the nature herein considered, for this must result in improperly 40 increasing the proportions of the machine in those dimensions most undesirable for floor-space economy, namely length and width. The increased capacity herein sought is one which is the direct result of the maximum 45 increase in the length of a single continuous can-path, so that not only is the machine restricted in floor-space dimensions, but is also adapted for the now almost universal and approved practice of single can- 50 lines.

It is the object of my invention, therefore, to provide a cooker of the rolling-can

type in which the can path is so arranged and directed as to have maximum length consistent with minimum floor-space dimensions of the box in which it is laid. 55

To this end my invention consists in the novel cooker which I shall now fully describe, by reference to the accompanying drawings, in which— 60

Figure 1 is a vertical, longitudinal section of my cooker, on the line $x-x$ of Fig. 2, the cover of the box being omitted. Fig. 2 is a top plan view, broken, of the same. Fig. 3 is a vertical, cross section, enlarged, on the line $y-y$ of Fig. 1. Fig. 4 is a vertical cross section on the line $z-z$ of Fig. 1. Fig. 5 is a vertical section on the line $w-w$ of Fig. 1, looking from the inside outwardly in the direction of the arrow 70 on the section-line. In this view the chains and pusher bars are omitted. Fig. 6 is a detail sectional view showing the construction of the bearings for all the shafts which are mounted in the sides of the cooker box. 75 Fig. 7 is a detail fragmentary view of the endless traveling chain, showing the attachment of the pusher-bars.

1 is a box having a removable chambered cover 2, which is best fitted in a water seal at 3, as shown in Fig. 3. Suitable means are provided for heating the box, as, for example, a water content 4 and steam-pipes 5 controlled by a cock at 6, said pipes being perforated in order to admit live steam. A 80 controllable drain for the box is shown at 7, in Fig. 1. Supported within the box are the track-rails 8 which form the can-path. The rails are all of angle section, those at each side being of L-section and the intervening ones of T-section, as well shown in Fig. 3. They are all carried by suitable cross-supports 9.

10 is a fixed guide plate spaced from and parallel with the track-rails and following 95 throughout their general tortuous path. This plate is carried by cross supports 10' and coacts with the tracks to support and guide the cans in their path. It is a single plate having a width equal to the width of 100 the whole can-path, overlying the track-rails in some courses and underlying them in others.

The courses of the can-path as formed be-

2
tween adjacent track-rails are as follows: From the point of beginning, where the feed chute 11 leads to the box-inlet 12, as seen in Fig. 4, the path extends horizontally 5 and longitudinally of the box near and parallel with one of its sides to near the other end of the box, where it curves downwardly in a vertical plane to a lower horizontal plane, in which it thence extends 10 horizontally in the vertical plane of and parallel with its upper course, back toward the first end of the box; and at the terminal of this second course, it curves again downwardly in the same vertical plane to a third 15 lower horizontal plane, in which it again extends horizontally, parallel with the second course and still in the same vertical plane, to the rear end, where it once more curves downwardly in a vertical plane to 20 the lowest horizontal plane, in which it extends toward the first end horizontally and parallel with the overlying courses and in the same vertical plane thereof. By the completion of this lowest course, there is 25 constituted what may be termed, for the sake of clearness in description, a zig-zag, vertically disposed unit, that is, one with a series or plurality of turns or bends in succession, all the courses of said unit lying in 30 the same vertical plane preferably parallel with the side of the box and perpendicular to its base. At the end of this first unit the can-path continues by means of a path section, shown in Fig. 5, and specifically designated by the numeral 13, said section extending at an angle with the plane of said path unit, to the beginning of the second path unit, which beginning lies in the upper 35 portion of the box. This second unit is precisely similar to the first, lying parallel therewith and its several zig-zag courses all lying in the same vertical plane. At the end of this second unit, the path continues, by means of a second inclined path section 13, 40 to the beginning of a third unit, which is coextensive with and parallel with the second unit, and said third unit joins a fourth similar and similarly disposed unit, by a third inclined path section 13; and thenceforward, similarly, throughout as 45 many units as may be desired, the end of the last unit communicating with the can exit 14 of the box and the delivery chute 15. Now, in order to advance the cans throughout the 50 entire length of this single continuous path, pusher bars 16 are provided. These bars extend transversely of the width of the combined units. They are carried by endless traveling chains 17 one on each side. 55 The chains are mounted on driving sprockets 18 and guide sprockets 19, and travel by means of their joint rollers 34 on the cross supports in the box, as shown in Fig. 3. They are parallel with the sides of 60 the box and they and their pusher bars 16

follow the courses of the vertical units of the can-path, the bars being always at right angles to said path, except in that portion involving the inclined connecting sections 13.

The chains are driven by the shaft 20 70 upon which the sprockets 18 are mounted, said shaft deriving motion from a worm gear 21 on its end, with which meshes a worm pinion 22 on the driving shaft 23 carrying the usual fast and loose pulleys 75 at 24.

At 25, as seen in Figs. 1 and 2, is indicated a chain-tightener.

Where the several sprocket shafts are mounted in the box walls, a steam tight 80 bearing is provided, such, for example, as is shown in Fig. 6, by the stuffing boxes comprising the outer sleeve 26, the telescopic clamping glands 27 and 28 with intervening packing 29 and the bolts 30 to 85 clamp said glands upon the packing. The gland 28 has a head 31 between which and the head of the sleeve 26 is a gasket 32. The pusher-bars 16 may be of any suitable construction and secured suitably to the 90 endless traveling chains. A good construction is that shown in Fig. 7. The link pivot-bolts 33 which carry the rollers 34 are extended at one end, to serve as bearings for the hollow cylindrical pusher bars 16. 95

In operation, the cans roll in single line through the inlet 12 upon the beginning of the can-path. The cans rest upon and between adjacent track-rails 8, and are rolled along, by the pusher bars 16. Any given 100 can follows the zig-zag first unit of the path being guided by the plate 10, and when it reaches the end of said first unit it is still advanced and is lifted along the inclined connecting section 13 of the path to the beginning of the second path unit, the transfer from the first to second unit being easily effected by reason of the can slipping bodily longitudinally of the pusher bar. Thereafter said can is advanced by the same 110 pusher bar throughout the vertically tortuous second path-unit, and thence by the same pusher bar is transferred to the third path unit, and so on until it emerges from the exit 14. When the box is full of cans, 115 there is thus a transverse row of cans in front of each pusher-bar, the whole can-content representing a continuously moving single line from the inlet to the outlet of the cooker. 120

It must be noted that the height of the box within reasonable limits, is not of importance, for this dimension is not involved in floor-space economy. It is possible, therefore, to secure a relatively long path by 125 having a maximum number of courses in a vertically disposed path-unit, and then by increasing the number of said units and connecting them by short sections, to enjoy the advantage of their combined maximum 130

lengths, resulting in the longest possible single continuous path consistent with a given length and width of the box.

I am aware that to-and-fro can paths in 5 cookers are not new *per se*, and that such a course has been arranged in both horizontal and vertical planes. I am also aware that a plurality of side by side, duplicate, independent to-and-fro courses have been disposed in 10 a vertical plane, adapted for plural can-lines, that is, for a can to pass into, through and out of one of said courses only, without continuing into an adjacent or duplicate course. I am aware also of a single continuous spirally or helically directed can-path arranged 15 in various planes; but I am not aware of a single, continuous can-path comprising a plurality of vertically disposed, parallel, zig-zag can-path units, with connecting sections.

The zig-zag path when formed as herein shown and described, with the bend at the crossing-section end having the full height of the path-unit and the bends at the other 25 end being narrower, is of advantage in that it affords opportunity at the full-height bend to admit and to deliver the cans with accuracy and without interference from the traveling pusher-bars.

30 By feeding the cans at the inlet 12 at the proper point in the upper quadrantal section of the large bend, each can will roll in behind a receding pusher-bar without obstruction therefrom, and directly in front of an up-rising bar; and by delivering the cans at the 35 exit 14 at the proper point in the lower quadrantal section of said bend, each can tends by gravity to roll outwardly, as it has not reached a point of equilibrium. The path 40 at its other end, not having these considerations, can be directed in its zig-zag course by the plurality of narrower bends.

I claim:—

- 45 1. A cooker comprising a heating box with a can inlet and a can outlet and having within it a can path throughout whose length the cans progress from the inlet to the outlet, said path being formed of a plurality of parallel zig-zag units the successive courses of each of said units lying all in the same plane perpendicular to the base of the box, and the end of one unit being joined to the beginning of the succeeding unit by a crossing section of the path; and means for advancing the cans throughout the entire length of said path.
- 50 2. A cooker comprising a heating box with a can inlet and a can outlet and having within it a can path throughout whose length the cans progress from the inlet to the outlet, said path being formed of a plurality of parallel zig-zag units the successive courses of each of said units lying all in the same plane perpendicular to the base of the box, and the lower end of one unit being connected with
- 55 the upper end of the succeeding unit by an inclined section of the path; and means for advancing the cans throughout the entire length of said path.
- 60 3. A cooker comprising a heating box with a can inlet and a can outlet and having within it a can-path throughout whose length the cans progress from the inlet to the outlet, said path being formed of a plurality of parallel zig-zag units the successive courses of each of said units lying all in the same plane perpendicular to the base of the box, and the end of one unit being joined to the beginning of the succeeding unit by a crossing section of the path, said path being composed of spaced track-rails and a single plate spaced from and following the course of said rails and having a width equal to the whole width of path within the box; and means for advancing the cans throughout the entire length of said path.
- 65 4. A cooker comprising a heating box with a can inlet and a can outlet and having within it a can path throughout whose length the cans progress from the inlet to the outlet, said path being formed of a plurality of parallel zig-zag units the successive courses of each of said units lying all in the same plane perpendicular to the base of the box, and the lower end of one unit being connected with the upper end of the succeeding unit by an inclined section of the path, said path being composed of spaced track-rails and a single plate spaced from and following the course of said rails and having a width equal to the whole width of path within the box; and means for advancing the cans throughout the entire length of said path.
- 70 5. A cooker comprising a heating box with a can inlet and a can outlet, and having within it a can path throughout whose length the cans progress from the inlet to the outlet, said path being formed of a plurality of parallel zig-zag units the successive courses of each of said units lying all in the same plane perpendicular to the base of the box, and the end of one unit being joined to the beginning of the succeeding unit by a crossing section of the path, said path at its crossing section end having a bend equal in height to the full height of the unit and at its other end having a plurality of narrower bends with an intervening return bend; and means for advancing the cans throughout the entire length of said path.
- 75 6. A cooker comprising a heating box having within it a can-path throughout whose length the cans progress from the inlet to the outlet, said path being formed of a plurality of parallel zig-zag units the successive courses of each of said units lying all in the same plane perpendicular to the base of the box, and the end of one unit being joined to the beginning of the succeeding unit by a crossing section of the path, said path at its

crossing section having a bend equal in height to the full height of the unit and at its other end having a plurality of narrower bends with an intervening return bend; a traveling series of pusher-bars following the course of said path to advance the cans therethrough; means for admitting the cans to the can-path at a point in the upper quadrantal section of its full-height bend; and means for

delivering the cans at a point in the lower 10 quadrantal section of said bend.

In testimony whereof I have signed my name to this specification in the presence of two subscribing witnesses.

ALBERT R. THOMPSON.
